UNITED STATES PATENT OFFICE.

CONRAD MILLER, OF WASHINGTON, DISTRICT OF COLUMBIA.

DESIGN FOR A CLASP.

SPECIFICATION forming part of Design No. 25,507, dated May 19, 1896.

Application filed April 9, 1896. Serial No. 586,876. Term of patent 14 years.

To all whom it may concern:

Be it known that I, CONRAD MILLER, a citizen of the United States, residing at Washington, in the District of Columbia, have invented and produced a new and original Design for a Hose-Supporting Clasp, of which the following is a specification.

I have illustrated my design in the accompanying drawings, forming a part of this application.

In the drawings, Figure 1 is a front view, Fig. 2 is a side view, and Fig. 3 a rear view, these three views being deemed necessary to fully illustrate my design.

The leading feature of my design consists in the recessed back plate and the plain front plate, a recess being formed between the front and rear plates by the hooked formation of

projections from the rear plate engaging the lower edge of the front plate. The front plate is of less depth than the hooks of the rear plate, and these hooks accordingly project below the plate with their free ends engaging the bottom edge of the plate.

In the drawings, *a* is the rear plate, *b* the recesses in the said plate, and *c* the hooked ends of said plate. The front plate is shown at *d* as having a plain front with a slightly-flanged lower edge.

What I claim is—

The design for a hose-supporting clasp herein shown and described.

CONRAD MILLER.
